PORTABLE TUBE TESTER FOR VACUUM TUBES

Jacob Anthes, Atkinson, Wis.

Application May 31, 1957, Serial No. 46,430

Term of patent 14 years

(Cl. D26—1)

FIG. 1.

FIG. 2.

FIG. 3.Figure 1 is a top plan view of a portable tube tester for vacuum tubes, showing my new design;

Figure 2 is a front elevational view; and

Figure 3 is a perspective view thereof.

The broken line showing of legible matter and of a cover in Figure 2 is for illustrative purposes only. A portion of the drawing figures is diagonally lined to indicate transparency.

I claim:

The ornamental design for a portable tube tester for vacuum tubes, as shown and described.
